[54] HOUSING FOR PHOTOELECTRIC SENSOR
AND CONTROL CIRCUIT RESPONSIVE
THERETO

[75] Inventor: **Anthony R. Lazzara**, Portola Valley,
Calif.

[73] Assignee: **Scientific Technology, Inc.**, Mountain
View, Calif.

[**] Term: **14 Years**

[21] Appl. No.: **884,038**

[22] Filed: **Mar. 6, 1978**

[51] Int. Cl. .... **D13—99; D13—03**

[52] U.S. Cl. **D13/99; D13/41**

[58] **Field of Search** **D10/104, 106, 121;**

CLAIM

The ornamental design for a housing for photoelectric sensor and control circuit responsive thereto, as shown and described.

DESCRIPTION

FIG. 1 is a perspective view of the housing for photoelectric sensor and control circuit responsive thereto showing my new design;

FIG. 2 is a plan view on reduced scale thereof;

FIG. 3 is a side view on reduced scale thereof;

FIG. 4 is a bottom view on reduced scale thereof;

FIG. 5 is a left-hand view on reduced scale thereof; and

FIG. 6 is a right-hand view on reduced scale thereof.
